FIG. 5.

INVENTOR

JOHN W. CLOUD

BY *Wm. M. Cady*

ATTORNEY

UNITED STATES PATENT OFFICE.

JOHN WILLS CLOUD, OF LONDON, ENGLAND.

CONTROLLING DEVICE FOR ELECTRIC CIRCUITS.

Application filed August 15, 1923. Serial No. 657,554.

To all whom it may concern:

Be it known that I, JOHN WILLS CLOUD, a subject of the King of Great Britain and Ireland, residing at London, England, have 5 invented a certain new and useful Improvement in Controlling Devices for Electric Circuits, of which the following is a specification.

This invention relates to electric switches 10 for the control of power, heating, or lighting circuits, and has for its object to provide an improved device for this purpose whereby a greater degree of safety and economy in current consumption may be obtained.

15 In connection with electrically operated apparatus such as electric irons, lamps, or the like, it is usual to provide a manually operated switch whereby the supply of operating current to the apparatus can be cut off 20 when desired. Experience has shown, however, that the operator is liable to leave the apparatus without first opening the switch with the result that not only is there a risk of the apparatus becoming dangerously over-heated but also a considerable waste of electrical energy is occasioned.

The invention is illustrated in the accompanying drawings, of which Figure 1 is a 30 sectional plan view of a door or gate provided with one form of mechanism embodying the principle of the invention; Figure 2 being a sectional view on the line II-II of Figure 1; Figure 3 is a view similar to Figure 1 illustrating another form of mechanism embodying the invention; Figure 4 being a sectional view of the retaining device of Figure 3; Figure 5 is a view similar to Figure 1 illustrating a modified form of mechanism which may be employed.

40 Referring now first to the construction shown in Figures 1 and 2, the door or gate of the room or enclosure in which the electrically operated apparatus is located is indicated at 1, the jamb 2 of the door being 45 provided with a retaining device indicated at 3. The latter comprises a cylindrical casing 4 embedded in the jamb 2 of the door, a sleeve or bushing 5 open at one end being 50 adapted to slide within the casing 4 as clearly shown in Figure 1.

The closed end of the bushing 5 is secured 55 to an operating member 6 accommodated within a longitudinal slot 7 formed in the outer side of the casing 4. A helical controlling spring 8 is interposed between the inner end of the casing 4 and the bushing 5,

the latter of which is traversed by a rod 9, the inner end of the rod 9 being surrounded by the controlling spring 8 and the outer end of this rod projecting from the surface of 60 the jamb 2 towards an electric switch 10 here shown as of the tumbler type. The switch 10 is so arranged that when the rod 9 is in the position shown in Figure 1 in which it is maintained by the controlling 65 spring 8 when the door 1 is open, the extreme end of the rod 9 is closely adjacent to the operating knob 11 of the switch when in its "off" position. The outer face of the door 1 is adapted to engage during its final 70 closing movement with a tongue or projection 12 formed on the member 6, the final closing movement of the door 1 displacing the tongue towards the right until the tongue 12 lies in a slot 13 when the door 1 is fully 75 closed, in which position the extreme end of the rod 9 is moved clear of the knob 11 of the switch 10 thus permitting the latter to be set to its "on" position.

The switch 10 is included in the circuit of 80 the electrically operated apparatus and may itself constitute the ordinary controlling switch for this apparatus or may be an additional switch included in series with the usual controlling switch.

85 The operation of the mechanism is as follows:

So long as the door 1 is open the rod 9 is maintained by the action of the controlling spring 8 in the position shown in Figure 1 in which the knob 11 of the switch 10 is positively maintained in its "off" position and cannot be moved to its "on" position to enable the circuit of the electrically 90 operated apparatus to be closed. The complete closure of the door 1 moves the tongue or projection 12 towards the right, this projection carrying with it the operating member 6 and the sleeve 5 against the opposing action of the spring 8. The rod 9 is 95 thus, when the door is fully closed, withdrawn towards the right and the knob 11 of the switch 10 can then be set to its "on" position, indicated in dotted lines at 11'. The circuit of the electrically operated 100 apparatus is thus completed at the switch 10 and operating current may be supplied to the apparatus controlled by this switch. In the event, however, of the door 1 being 105 opened, the controlling spring 8 will evidently cause the rod 9 to be moved outwards and by engagement with the knob 11 of the

switch 10 to return this switch to its "off" position.

It will be observed that the retaining device 3 thus acts to set the switch 10 automatically to its "off" position when the door is opened, although the reclosure of the door does not move the switch 10 to its "on" position, this action being effected manually when permitted by the withdrawal 10 of the rod 9 when the door 1 is fully closed.

It will thus be seen that in order that the circuit of the electrically operated apparatus may be completed the door 1 must first be completely closed and the switch 10 15 must then be set into its "on" position which can only be effected from within the room or enclosure after the door 1 has been fully closed.

In the mechanism illustrated in Figures 20 3 and 4 the construction of the retaining device 3 is somewhat different from that above described, the rod 9 being adapted to slide within a cylindrical casing 14, the inner end of this rod being connected by 25 means of a transverse pin or bolt 15 to a plunger 16 adapted to slide within a cylindrical extension 17 of the casing 14 containing the controlling spring 8.

The plunger 16 is adapted to be operated 30 by the final closing movement of the door 1 so as to cause the rod 9 to be withdrawn from the knob 11 of the switch 10 against the action of the spring 8. In other respects the operation of the mechanism shown in 35 Figures 3 and 4 is identical with that above described.

It will be observed that in the constructions illustrated in Figures 1 to 4 inclusive 40 the setting of the switch 10 to its "off" position is effected by the action of the controlling spring 8 when the door 1 is opened and it is therefore essential that the strength of the spring 8 should be sufficient for this purpose.

45 In the modified construction illustrated in Figure 5 the setting of the switch 10 to its "off" position when the door is opened is arranged to be effected under certain conditions positively by means of the door 1 itself, the knob 11 of the switch 10 being provided with an extension 18 adapted to be engaged by a striker plate 19 of rubber or other suitable material attached to the inner face of the door at the edge thereof as 50 shown.

55 It will be seen that when the door 1 is in its closed position indicated in full lines in Figure 5, the rod 9 is maintained in its retracted position and the switch 10 can therefore be set to its "on" position.

60 During the opening movement of the door 1 and when the inner face of the door attains the position indicated in dotted lines at 1', the striker plate 19 engages with the 65 extension 18 of the switch 10 and the con-

tinued movement of the door thus set the switch 10 to its "off" position unless this has already been previously effected by the action of the rod 9 and its co-operating spring 8 as would normally be the case. 70 Under these conditions, the extension 18 occupies the position shown in dotted lines in the figure from which it will be seen that during the reclosing movement of the door the latter does not engage with the 75 projection 18 the switch 10 being thus left in its "off" position from which it may be set to its "on" position as soon as the door 1 is fully closed and thereby causes the withdrawal of the rod 9 as above described. 80

85 The arrangement illustrated in Figure 5 may obviously be modified in such a manner that the door 1 or a striker element carried thereby will engage with the extension 18 on the switch 10 prior to the engagement of the end of the rod 9 with the knob 11 in which case it will be seen that the switch is always positively moved to its "off" position by the door itself.

90 The invention may evidently also be applied with advantage to switches for controlling electric lighting circuits so as to prevent, for instance, an electric lamp from being left alight when a room is unoccupied.

95 In this case the switch automatically controlled by the opening and closing of the door of the room may be supplemented by a pilot switch and a pilot lamp so arranged that the pilot switch which is closed either manually or automatically 100 when the door is opened causes the pilot lamp to be illuminated. This lamp which may conveniently be located adjacent to the main switch being arranged to be automatically extinguished when the main switch is manually closed to render the lamp or lamps of the room operative. 105

110 It will be understood that in the case of there being more than one door or gate to the enclosure containing the electrically operated apparatus to be controlled, an additional switch will be provided at each such door or gate, so that the circuit of the electrically operated apparatus will be automatically opened in the event of any of the doors or gates being opened. 115

120 The construction of the mechanism for operating the switch in the manner above described may evidently be varied in many respects without exceeding the scope of the invention.

125 Having now described my invention, what I claim as new and desire to secure by Letters Patent, is:—

1. The combination with a manually operable member for operating an electric switch, of a movable barrier, a rod movable to engage and shift said member to "off" position, a spring tending to move said rod and thereby said member to "off" position, 130

- and an element associated with said rod and operated by the movement of said barrier to its closed position for moving said rod out of engagement with said member.
- 5 2. The combination with a manually operable member for operating an electric switch, of a movable barrier, a casing, a sleeve slidably mounted in said casing, a rod secured to said sleeve and movable to engage and shift said member to "off" position, a spring tending to move said sleeve and rod to "off" position, and an element movable with said rod and positioned to be engaged by said movable barrier for shifting said sleeve and rod out of engagement with said member upon movement of said barrier to closed position.
- 10 3. A movable barrier, an electric switch operating arm having an "off" and an "on" position, a longitudinally movable rod disposed to engage said arm, a spring tending to shift said rod and thereby said arm to
- 15 its "off" position, and an element carried by said rod and operable by said movable barrier upon movement to its closed position 25 for moving said rod out of engagement with said arm to permit manual movement of said arm to its "on" position.
4. The combination with a movable barrier, of an electric switch operating arm, 30 a casing, a sleeve mounted in said casing, a rod carried by said sleeve and adapted to engage said arm, a spring mounted in said casing and engaging said sleeve, a member movable with said sleeve and having a portion engageable by said barrier, the movement of the barrier to its closed position operating said member to shift said sleeve and rod against the pressure of said spring 35 to a position permitting the free manual 40 operation of said switch arm.

In witness whereof I have hereunto set my hand.

JOHN WILLS CLOUD.
